UNITED STATES PATENT OFFICE.

JOHN PRESSLEY COLEMAN, OF EDGEWOOD, PENNSYLVANIA, ASSIGNOR
TO THE UNION SWITCH & SIGNAL COMPANY, OF SWISSVALE, PENNSYLVANIA, A CORPORATION OF PENNSYLVANIA.

RAILWAY-SIGNAL.

SPECIFICATION forming part of Letters Patent No. 761,208, dated May 31, 1904.

Application filed September 4, 1903. Serial No. 171,940. (No model.)

To all whom it may concern:

Be it known that I, JOHN PRESSLEY COLEMAN, a citizen of the United States, residing at Edgewood, in the county of Allegheny and 5 State of Pennsylvania, have invented certain new and useful Improvements in Railway-Signals, of which the following is a specification.

My invention relates to railway-signals, and particularly to that class of railway-signals 10 which employ fluid-pressure as a motive power.

My invention has especial reference to this type of railway-signal when it is controlled by a lever, which may be located in a tower.

15 I will describe a railway-signal embodying my invention and then point out the novel features thereof in the claims.

In the accompanying drawings, Figure 1 is 20 a view, partly in elevation, partly in vertical section, and partly in diagram, of a railway-signal and the controlling means therefor embodying my invention. Fig. 2 is a view, partly in vertical section and partly in elevation, of a portion of the apparatus or mechanism embodied in the railway-signal illustrated in Fig.

25 1. Fig. 3 is a detail elevational view. Figs. 2 and 3 are drawn to a larger scale than Fig. 1.

Similar letters of reference designate corresponding parts in all of the figures.

30 I will premise that wherever I herein use the term "signal" I mean a visual signal device which by its position relatively to its support or by its color gives indication of the service condition of the railroad track or

35 section of railroad-track which it governs.

Also wherever I herein use the term "fluid-pressure" I mean a liquid or gas under pressure. I preferably employ a gas. Any gas may be employed—as, for example, air or 40 carbonic-acid gas—and under any pressure which is sufficient or more than sufficient to operate the apparatus or mechanism for moving the signal. If the pressure of the gas or liquid be above that required for the operation of the apparatus or mechanism for moving the signal, reducing-valves may be employed in their proper places.

Referring now to the drawings, A design-

nates a visual signal device, here shown as being of the semaphore type, and comprising, 50 as usual, a blade *a* and a casting *a'*, sometimes called a "spectacle," which moves the blade to one position of indication when the signal device is not free to move—that is, when the device is not held by any agency or means— 55 as, for example, fluid-pressure—in a position indicating "caution" or "safety." The signal device is therefore biased to one position of indication, generally the horizontal position, which indicates "danger" or "stop." 60 The signal device is pivoted, as usual, on a post or other support *A'*, and it is moved from one position of indication to another, generally from the horizontal position of indication to an inclined position, which indicates 65 "clear," "safety," or "caution," through the agency of a rod *B*. One end of the rod *B* is operatively connected with the signal device, and the other end is operatively connected with a fluid-pressure apparatus or 70 mechanism or other apparatus or mechanism which is designed to move the signal device from one position of indication to another.

D designates a fluid-pressure apparatus or mechanism for moving the signal from one 75 position of indication to another. It is here shown as being in the form of a motor consisting of a piston *d* and a cylinder *d'*, within which the piston moves. Fluid-pressure for operating the apparatus D is supplied through 80 a pipe or conduit *d''* leading from any desired source of fluid-pressure supply.

d'' designates a valve or cock in the pipe or conduit *d''*. The passage of the fluid-pressure to the apparatus is governed aside from the 85 valve *d''* by an electrically-operated valve device E. The valve device E may conveniently be substantially of the form and arrangement illustrated and described in United States Patent No. 357,109, issued February 1, 1887, to 90 George Westinghouse, Jr., for electrical interlocking mechanism for switches and signals, to which patent reference may be had. It is only necessary to here state any electrically-operated valve device employed should have 95 the function of opening the supply of fluid-

pressure when the magnet comprised in the device is energized and of closing or cutting off the supply of fluid-pressure when said magnet is deenergized and opening an exhaust port or passage to the atmosphere.

e e' designate valves which are moved or operated when the magnet is energized. The valve e opens and closes the port through which the fluid-pressure passes to the cylinder d' , and the valve e' opens and closes the port e^3 through which the fluid-pressure escapes from the apparatus to the atmosphere. It will be understood that when the valve e is unseated the valve e' will be seated, and vice versa.

The operation of the railway-signal so far as described will be readily understood. Upon the closing of the circuit, including the magnet of the electrically-operated valve device, which magnet is inclosed by the casing e^3 , the valve e will be unseated to permit the fluid-pressure to pass into the cylinder and move the piston therein to the lower portion of the cylinder. The rod d^4 of the piston d is connected to one end of a pivoted lever d^5 , and the other end of the lever is connected with the end of the rod B . The downward movement of the piston causes the lever d^5 to be rocked on its pivot, and the signal device through the rod B is moved from the horizontal position of indication to an inclined position of indication. The signal device will be held in the inclined position of indication so long as the piston d is acted upon by the fluid-pressure. When the signal device is to be moved to the horizontal position of indication through gravity acting on the counterweight a' , the supply of fluid-pressure is cut off from the cylinder, and this is preferably accomplished by opening the circuit of the magnet of the electrically-operated valve device. When the magnet is deenergized, the valve e is seated by the spring beneath it and the valve e' unseated at the same time, thereby allowing the fluid-pressure in the cylinder to escape through the port e^3 to the atmosphere.

The circuit in which the magnet of the electrically-operated valve device is included may be opened and closed in any desired manner.

In the present instance the circuit is opened and closed by means of a lever L , which may be located at any desired point—as, for example, in a tower. The lever L has connected with it a bridge-plate l , which slides upon a contact-plate l' and between two contact-plates l^2 l^3 —the one l^2 being for one signal (that illustrated in Fig. 1) and the other, l^3 , being for another signal. When the bridge-plate l is moved between the contact-plates l' and l^2 , (see dotted lines, Fig. 1,) a closed circuit will be established, which, starting from a battery Z , is wires 1 2, contact-plate l' , bridge-plate l , contact-plate l^2 , wires 3 and 4, magnet of the electrically-operated valve device, and wire 5, back to the battery. The magnet of the elec-

trically-operated valve device will shift the valves e e' from the position shown in Fig. 2 to a position in which the valve e' will be seated and the valve e opened. Fluid-pressure will then pass the valve e and through the passage e^4 to the cylinder d' to move the piston d to the lower end thereof and the signal from its horizontal position of indication, Fig. 1, to an inclined position of indication. When the lever L is moved back to the position shown in full lines, Fig. 1, the circuit of the magnet of the electrically-operated valve device will be broken, and the valves e e' will be moved to the positions shown in Fig. 2 by the spring e^6 . The fluid-pressure supply will then be cut off from the cylinder, and the fluid-pressure that may be in the cylinder will escape through the passage e^4 and port e^3 to the atmosphere, allowing the piston to move up in the cylinder due to the downward movement of the spectacle d' .

The lever L may be one of a number of levers which are arranged side by side in a frame, and these levers may be mechanically interlocked, which mechanical locking is so arranged that one lever is made to release or lock a certain other lever or levers, as service conditions may require. Ordinarily a lever controlling the position of a switch in a line of rails is interlocked with a lever controlling the position of a signal governing the passage of trains over the switch. These levers may also be mechanically interlocked with other levers controlling switches and signals which if not properly placed would give the right of way to trains over a route or routes which would conflict. A common example is that of a crossing. The crossing rails are usually provided with derail-switches and with signals governing the position of the derail-switches. Ordinarily the derail-switches in one or both the crossing lines of the railway are open, and the signals governing the passage of trains over the derail-switches are in the horizontal or danger position of indication. With this condition the levers controlling the derail-switches and signals are so interlocked that before the signal can be cleared all derail-switches on the same line will have to be closed, and, conversely, before the derail-switches can be opened the signals controlling the passage of trains over them have to be set to the danger position. When a clear route is set up on one of the crossing lines, all the derail-switches or signals on the line to be crossed are in such positions as to stop a train. It sometimes happens that an operator attempts to change the clear route for a train to a danger one, even while a train is approaching on the clear route. In order to prevent this being done until after a lapse of time, which may be predetermined, I have provided means which will give a "slow release" to a lever or lever to be moved to change a route.

In order that the slow release may be ac-

complished, an electric lock is preferably provided for each lever, which electric lock, as shown in the drawings, comprises an electromagnet M and an armature m, which is operated by the electromagnet. The armature m is adapted to engage under certain conditions a rod m', connected with the lever L, and to prevent the lever L being moved to its final position, and thus release other levers through the mechanical locking. As shown, the armature m is provided with a hook m², which is adapted to drop on either side of one or more projections m³, provided on the rod m', when the magnet M is deenergized. Ordinarily the circuit for the electromagnet is closed when the lever to which it is applied is in its normal position, thus permitting the lever to be freely moved from its normal to reversed position. In the form shown in Fig. 1 the normal position of the lever is that shown in full lines, and in this position the signal is in the horizontal or danger position. The circuit for the electromagnet, starting from the battery Z, is wires 1 6, electromagnet M, wire 7, circuit-breaker K, wire 8, a circuit-breaker N, and wires 9 and 5 to battery. The circuit-breaker K is operated from the piston d through a link k, which is connected with the piston, and a rod k', which is suitably guided in a bracket secured to the fluid-pressure mechanism. As shown, the circuit-breaker K comprises contact plates or springs k² k³ and a bridge-piece k⁴, carried by the rod k'. When the signal is moved from the horizontal or danger position to an inclined position of indication, which may be a clear or safety indication, the bridge-piece will be moved from between the plates k² k³, and thus break the circuit of the electromagnet. As soon as this is done the armature m will fall behind one of the projections m³ (the lever L having been previously moved to the dotted position) and will prevent the lever being put back to normal position until the bridge-piece k⁴ is again moved between the contact-plates k² k³ to again close the circuit of the electromagnet M and have it pick up its armature m. This will be when the signal is again in the horizontal position of indication. Until the signal is in this position the lever cannot be put in its former position to unlock other levers. The magnet M in addition to its locking function has the function of serving as an indicator that the mechanism or apparatus controlled by the lever has completed its function.

In addition to the circuit-breaker K the circuit-breaker N is provided in the circuit of the electromagnet and is in series with the circuit-breaker K. If the circuit-breaker K should be closed and the circuit-breaker N not closed, the electromagnet M would not be energized to pick up or attract the armature m to release the lever.

The circuit-breaker N is operated by a slow-

release mechanism. As shown, this slow-release mechanism comprises a chamber o, a diaphragm o', and an exhaust port or passage o², which is provided in the wall of the chamber and controlled by an adjustable valve o³. The chamber o is suitably mounted on the cylinder d and is in communication with the cylinder d through a passage o⁴, controlled by a check-valve o⁵. The diaphragm o' is located at the upper end of the chamber o and is held in position by a cap o⁶, provided for the chamber o. The diaphragm is provided with a stud or projection o⁷, which engages with a lever n, comprised in the circuit-breaker. A spring o⁸ is provided above the stud o⁷, the tension of which may be regulated by a screw o⁹ in the usual way. The purpose of the spring o⁸ is to regulate the movement of the lever n by the fluid-pressure under the diaphragm. The circuit-breaker N, as shown, comprises the lever n, pivoted at one end on a pin n', carried by brackets o¹⁰ on the cap o⁶ and having a conducting-pin n¹¹ at its free end and contact springs or plates n² n³, which are carried by binding-posts n⁴, suitably mounted on a cross-piece o¹¹ and insulated from each other. The conducting-pin n¹¹ is also insulated from the lever n.

When the signal is to be moved from the horizontal position of indication by fluid-pressure, the fluid-pressure passing into the cylinder d' also passes through the passage o⁴ past the check-valve o⁵ into the chamber o. After sufficient fluid-pressure has entered the chamber it acts upon the diaphragm o' to cause it, through its stud o⁷, to move the lever on its pivot and raise the contact-pin from between the two contact-springs n² n³. The diaphragm will be held raised until the fluid-pressure which has not escaped from the chamber through the port o² is insufficient to keep the diaphragm raised. When this occurs, the lever n will be forced downward by the spring to again have the contact-pin n' between the contact-springs n² n³. The escape of the fluid-pressure from the chamber o is regulated by the valve o³. By moving the valve o³ toward its seat considerable time will pass before the circuit-breaker n is closed, which period of time may be predetermined.

It will be understood that the invention is not limited in its application to a controlling-lever, but may be used in any connection where it is desired to have time elapse before a circuit-breaker comprised in a circuit is closed. Also while I have described my invention in connection with a lever controlling the operation of a fluid-pressure apparatus or mechanism for moving a signal it is equally applicable to a lever controlling the operation of a fluid-pressure apparatus for moving a railway switch or switches. Also my invention is equally applicable to any other power-operated apparatus or mechanism for moving

signals or switches and also to levers which have a direct mechanical connection with a signal or switch operating mechanism. Therefore in the claims wherever I use the term 5 "lever" I wish it understood that I mean a lever for controlling or operating any sort of apparatus, mechanism, or device for moving a signal or railway-switch unless otherwise specified.

10. What I claim as my invention is--

1. In combination with a lever, an electric lock for said lever comprising an electromagnet, a circuit for said magnet, a circuit-controller included in said circuit, and a pneumatically-operated means for controlling said circuit-breaker.

2. In combination with a lever, an electric lock for said lever comprising an electromagnet, a circuit for said electromagnet, a circuit-breaker included in said circuit; and means for operating said circuit-breaker, comprising a chamber having an exhaust-port, a diaphragm operable by fluid-pressure, and an adjustable valve for said exhaust-port.

25. 3. In combination with a fluid-pressure apparatus, a chamber mounted on the cylinder of said apparatus and in communication therewith, a check-valve controlling said communication, a diaphragm in said chamber, and a circuit-breaker operated by said diaphragm.

35. 4. The combination of a circuit-breaker, means for operating it comprising a chamber having an exhaust-port, a diaphragm operable by fluid-pressure, an adjustable valve for controlling said exhaust-port, and a fluid-pressure supply for said chamber electrically controlled.

40. 5. The combination of a circuit-breaker comprising a pivoted lever for moving a part of the circuit-breaker to open and close a circuit, and means for moving said lever, said means comprising a chamber having an exhaust-port and an adjustable valve for said port, a diaphragm operated by fluid-pressure for moving the lever in one direction and a spring for moving the lever in the opposite direction.

50. 6. The combination in a railway-signal, of a signal, a fluid-pressure apparatus for moving it from one position of indication to another, an electrically-operated valve device for controlling the supply of fluid-pressure to the fluid-pressure apparatus, a circuit for said electrically-operated valve device, a lever and means operated thereby for opening and closing said circuit, an electric lock for said lever, a circuit-breaker included in the circuit of said electric lock and means operated by fluid-pressure for controlling said last-mentioned circuit-breaker.

60. 7. The combination in a railway-signal, of a signal, a fluid-pressure apparatus for moving it from one position of indication to another, an electrically-operated valve device for controlling the supply of fluid-pressure to the

fluid-pressure apparatus, a circuit for said electrically-operated valve device, a lever and means operated thereby for opening and closing said circuit, an electric lock for said lever, a circuit-breaker included in the circuit of 70 said electric lock and means operated by fluid-pressure for controlling said last-mentioned circuit-breaker, said means having a slow exhaust for the fluid-pressure operating said means.

75. 8. The combination in a railway-signal, of a signal, a fluid-pressure apparatus for moving it from one position of indication to another, an electrically-operated valve device for controlling the supply of fluid-pressure to the 80 fluid-pressure apparatus, a circuit for said electrically-operated valve device, a lever and means operated thereby for opening and closing said circuit, an electric lock for said lever, a circuit-breaker included in the circuit of 85 said electric lock and means for operating said last-mentioned circuit-breaker, said means comprising a chamber in communication with a source of fluid-pressure supply, a diaphragm in said chamber and a slow exhaust for the 90 fluid-pressure contained in the chamber.

9. The combination in a railway-signal, of a signal, a fluid-pressure apparatus for moving it from one position of indication to another, an electrically-operated valve device for controlling the supply of fluid-pressure to the fluid-pressure apparatus, a lever and means for controlling a circuit including the electrically-operated valve device, an electric lock for said lever, a circuit for said electric lock, a circuit-breaker in the circuit for the electric lock, and means for moving said circuit-breaker, said means comprising a chamber in communication with the fluid-pressure apparatus, a diaphragm in said chamber influenced 105 by the fluid-pressure therein and which operated the circuit-breaker, and a slow exhaust for the fluid-pressure in said chamber.

10. The combination in a railway-signal, of a signal, a fluid-pressure apparatus for moving 110 it from one position of indication to another, an electrically-operated valve device for controlling the supply of fluid-pressure to the fluid-pressure apparatus, a lever and means for controlling a circuit including the electrically-operated valve device, an electric lock for said lever, a circuit for said electric lock, a circuit-breaker in the circuit for the electric lock, and means for moving said circuit-breaker, said means comprising a chamber in 115 communication with the fluid-pressure supply passing the electrically-operated valve device, a check-valve in said communication a diaphragm in said chamber influenced by the fluid-pressure therein and which operated the 120 circuit-breaker, and a slow exhaust for the fluid-pressure in said chamber.

11. The combination in a railway-signal, of a signal, a fluid-pressure apparatus for moving the signal device from one position of indica- 130

tion to another, an electrically-operated valve device for controlling the supply of fluid-pressure to the fluid-pressure apparatus, a lever and means operated thereby for controlling said circuit, an electric lock for said means, a circuit for said electric lock, and a circuit-breaker included in the circuit of the electric lock; and means operated by fluid-pressure for controlling said circuit-breaker, said means comprising a chamber in communication with the fluid-pressure apparatus and having an exhaust-port, a diaphragm in said

chamber for moving the circuit-breaker in one direction, a spring for moving the circuit-breaker in the opposite direction, and an adjustable valve for the exhaust-port. 15

In testimony whereof I have signed my name to this specification in the presence of two subscribing witnesses.
